WORKPIECE HOLDER

Frank Henry Hadley, Birmingham, England, assignor of one-half to Baron Cyril David Woolf, Birmingham, England.

Application July 8, 1944, Serial No. 544,083
In Great Britain October 22, 1943

5 Claims. (Cl. 81—38)

1

This invention has for its object to provide an improved holder or jig whereby a plurality of work-pieces can be securely held simultaneously in a manufacturing operation.

In the accompanying sheets of explanatory drawings:

Figure 1 is a side elevation, Figure 2 a part sectional plan, and Figure 3 a sectional end elevation, of a work-piece holder constructed in accordance with the invention, Figure 3 being taken on the line 3—3 of Figure 1.

Figures 4 and 5 are respectively a sectional side elevation and a part sectional plan illustrating a modified form of the invention.

In carrying the invention into effect as shown in Figures 1 to 3, I employ a cast iron or other base *a* which is formed at its upper side with a pair of parallel guides *b* having undercut inner sides. At one end of the guides *b* there is mounted on the base *a* a metal block *c* which is slidably adjustable between the guides and is securable by screws *d* or other means at any desired position on the base. On the block *c* is secured a stationary jaw *e*, one side of which is formed with a plurality of V or other notches *f* for locating the work-pieces *g*. Alternatively the stationary jaw may be formed by a number of separate pieces each formed with a notch and all secured together on the block in fixed relation. Also on the base *a* and between the guides *b* is adjustably secured by screws *h* or other means another metal block *i* carrying at the end adjacent to the stationary jaw *e* a plurality of jaws *j*, the latter being slidably relatively to each other and to their supporting block. Each of the slidable jaws *j* is formed with a V or other notch *k*, and these notches occupy positions respectively opposite to the notches *f* in the stationary jaw *e*.

Near the end of the block *i* remote from the slidable jaws *j*, there is slidably mounted between the guides *b* on the base *a*, a cross bar *m* serving as an operating member. This operating member *m* is movable by any convenient means, such as a cam *n* pivotally supported on a horizontal axis by a bearing *o* adjustably secured to the base *a*, the cam being adapted to act on the side of the operating member remote from the block *i*, and being provided with an actuating arm *p*. Alternatively the operating member *m* may be movable by a screw, wedge or the like. Motion is imparted from the operating member *m* to the individual slidable jaws *j* through any convenient resilient means such as that hereinafter described. After the work-pieces *g* have been

2

placed in position, the operating member *m* is caused to advance the slidable jaws *j* into contact with the work-pieces *g*. At first all the slidable jaws *j* may move simultaneously, but as soon as any one of them exerts a gripping action on its work-piece *g* it is arrested, but the others are free to continue their movement (usually to a small extent) until all the work-pieces are securely gripped. This continued movement is permitted by the above mentioned resilient means through which motion is imparted from the operating member *m* to the slidable jaws *j*.

To enable the required movement to be transmitted from the operating member *m* to the slidable jaws *j* I secure to each of these jaws a stem *q* which is slidably supported in a bore *r* in the block *i*, and which at the end remote from the associated jaw has formed on or secured to it a hollow cylindrical thrust piece *s*, the latter having a tapered outer end which is split so that it is contractile. Also I form in one side of the operating member *m* a plurality of conical recesses *t* adapted respectively to receive the tapered and split ends of the thrust-pieces *s*. Moreover, around each stem *q* at the inner end of its thrust piece *s* I arrange in the corresponding bore *r* in the block *i* a helical spring *l* which serves to retract the associated jaw *j* when the operating member *m* is released by the cam *n* or other means, the spring being supported at the end remote from the thrust piece by a shoulder *u* in the said bore, and being adapted to act on the inner end of the thrust piece. On advancing the operating member *m*, it simultaneously advances all the jaws *j*, but as soon as each of the latter is arrested by the corresponding work-piece *g* continued action of the operating member causes the split-tapered end of the thrust piece to be contracted, and this enables the operating member to cause each jaw to exert an effective grip on its work-piece. It will be seen, therefore, that the thrust pieces *s* serve, by virtue of their contractile ends, as the above mentioned resilient means through which motion is imparted from the operating member *m* to the slidable jaws *j*.

As shown, the screws *d*, *h* employed for securing the blocks *c*, *i* to the base *a*, pass through one of the guides *b* and act on the adjacent sides of the blocks through the medium of a pressure piece *v*.

Instead of being formed by the thrust pieces *s*, the resilient means above mentioned may have the form exemplified in Figures 4 and 5 in which the parts similar or analogous to those above de-

scribed are indicated by the same reference characters suffixed by 1. In this example the thrust pieces s^1 (which may be of solid form) and the stems q^1 are separate from each other and are slidably supported in coaxial relationship by opposite ends of the corresponding bores r^1 in the block i^1 , the stems being loaded by the springs t^1 which serve to retract the slidable jaws j^1 . Also the adjacent ends of the thrust pieces s^1 and stems q^1 are held in spaced relationship by helical springs w^1 which are situated between the said ends in the bores r^1 , and which form the aforesaid resilient means, the arrangement being such that when movement of any of the jaws j^1 under the action of the operating member m^1 is arrested by the corresponding work-piece g^1 , the associated spring w^1 is compressed by the continued action of the operating member, and this enables the operating member to cause each jaw j^1 to exert an effective grip on its work-piece.

Moreover, the block c^1 carrying the fixed jaw e^1 is secured to the base a^1 by screws d^1 passing through holes in the base, and the block i^1 carrying the movable jaws j^1 is adjustably secured to the base by screws h^1 passing through slots x^1 in the base, the guides provided for these blocks in the previously described example being dispensed with. Further, the operating member m^1 is secured to and carried by adjacent ends of a pair of parallel rods y^1 which pass through holes in and are slidably supported by the block c^1 carrying the fixed jaw e^1 , the other ends of the rods being interconnected by a cross bar z^1 carrying the cam n^1 . The latter is rotatable about a vertical axis by an actuating arm p^1 , and is adapted by co-operation with the adjacent side of the block c^1 to impart movement through the operating member m^1 , thrust pieces s^1 , springs w^1 , and stems q^1 , to the slidable jaws j^1 . At a position beneath the jaws j^1 the base is formed with a transverse slot 2^1 , and beneath this slot there is arranged a parallel bar 3^1 carrying adjustable abutments 4^1 for the work-pieces g^1 , these abutments having the form of vertical pegs in screw thread engagement with the said bar, and the latter being adjustably secured to the base a^1 , by screws 5^1 passing through slots 6^1 in the base.

In other respects the example shown in Figures 4 and 5 is essentially similar to that shown in Figures 1 to 3.

The invention is not, however, limited to the examples above described as subordinate details of construction may be varied to suit different requirements. Further, I may duplicate the gripping means in either of the examples above described by mounting two sets of separately slidable jaws on the same base, and arranging for these to be actuated simultaneously from a common source of motion.

Having thus described my invention what I claim as new and desire to secure by Letters Patent is:

1. A work-piece holder comprising the combination of a base, a stationary jaw provided on the base and to form an abutment for a plurality of work-pieces, a plurality of separate and relatively slidable jaws adapted to co-operate

with the stationary jaw for securing the work-pieces, a stationary support provided on the base and slidably supporting the slidable jaws; an operating member for advancing all the slidable jaws towards the stationary jaw, springs arranged to bear against the said support and act on the slidable jaws for retracting the slidable jaws, and resilient means through which simultaneous and independent movements can be transmitted from the said member to the slidable jaws.

2. A work-piece holder as claimed in claim 1 and having arranged between the slidable jaws and the operating member, stems secured to the slidable jaws, and thrust pieces on the ends of the stems remote from the slidable jaws, the thrust pieces having contractile outer ends and serving as the resilient means through which movements can be transmitted from the operating member to the slidable jaws, and the operating member having recesses whereby the outer ends of the thrust pieces can be contracted when movements of the corresponding slidable jaws by the operating member are obstructed.

3. A work-piece holder as claimed in claim 1 and having arranged between the slidable jaws and the operating member, stems secured to the slidable jaws, thrust pieces arranged coaxially with and spaced from the outer ends of the stems, and springs arranged between the adjacent ends of the stems and thrust pieces and serving as the resilient means through which movements can be transmitted from the operating member to the slidable jaws, the operating member being adapted to act on the slidable jaws through the medium of the thrust pieces, springs, and stems.

4. A work-piece holder as claimed in claim 1 and having arranged between the slidable jaws and the operating member, stems secured to the slidable jaws, and thrust pieces on the ends of the stems remote from the slidable jaws, the thrust pieces having contractile outer ends and serving as the resilient means through which movements can be transmitted from the operating member to the slidable jaws, the operating member having recesses whereby the outer ends of the thrust pieces can be contracted when movements of the corresponding slidable jaws by the operating member are obstructed, and the stems having combined therewith the springs for retracting the slidable jaws after the latter have been moved by the operating member.

5. A work-piece holder as claimed in claim 1 and having arranged between the slidable jaws and the operating member, stems secured to the slidable jaws, thrust pieces arranged coaxially with and spaced from the outer ends of the stems, and springs arranged between the adjacent ends of the stems and thrust pieces and serving as the resilient means through which movements can be transmitted from the operating member to the slidable jaws, the operating member being adapted to act on the slidable jaws through the medium of the thrust pieces, springs, and stems, and the latter having combined therewith the springs for retracting the slidable jaws after the latter have been moved by the operating member.

FRANK HENRY HADLEY.
